US0D1031426S

(12) United States Design Patent (10) Patent No.: US D1,031,426 S
(45) Date of Patent:  Jun. 18, 2024

(54) HOLDER

(71) Applicant: GREEN MANATEE LLC, Chester Springs, PA (US)

(72) Inventors: Jordan Cooperman, Chester Springs, PA (US); Zhanni Gao, Chester Springs, PA (US); Jared Long, Wichita, KS (US)

(73) Assignee: Green Manatee, LLC, Chester Springs, PA (US)

() Term: 15 Years

(21) Appl. No.: 29/865,486

(22) Filed: Jul. 27, 2022

(51) LOC (14) Cl. 08-08

(52) U.S. Cl.

USPC D8/394; D30/199

(58) Field of Classification Search

USPC D8/324, 382, 394, 395, 396; D19/65; D3/207, 215; D30/166, 199

CPC F16B 45/02; F16B 1/00; B60R 16/0215; A44D 2203/00
